UNITED STATES PATENT OFFICE.

JEROME JOSIAH WEBSTER AND WILLIAM WALKER DREW, OF SOMERVILLE, MASSACHUSETTS, ASSIGNORS TO THE BOSTON CASH INDICATOR AND RECORDER COMPANY, OF BANGOR, MAINE.

CASH INDICATOR AND REGISTER.

SPECIFICATION forming part of Letters Patent No. 393,089, dated November 20, 1888.

Application filed January 30, 1888. Serial No. 262,346. (No model.)

To all whom it may concern:

Be it known that we, JEROME JOSIAH WEBSTER, a subject of Victoria, Queen of the United Kingdom of Great Britain and Ireland, and WILLIAM WALKER DREW, a citizen of the United States, both residing at Somerville, in the county of Middlesex and Commonwealth of Massachusetts, have invented a certain new and useful Improvement in Cash Indicators and Registers, of which the following is a specification.

Our invention relates to cash indicators and registers; and it consists in means for locking and unlocking the signals, independent means of preventing the registering-lever and the registering-ratchet from being carried too far by their respective momentums, and thereby registering too much, means of ringing the alarm-bell, and in the combinations herein-
after described and claimed.

In the accompanying drawings, on three sheets, Figure 1 is an isometric view of the mechanism of a cash indicator and register constructed according to our invention; Fig. 2, a rear elevation of a part of the same, showing the signals, signal-rods, the grid, its operating-spring, its locking-hook, the locking-rod, and means of connecting said locking-rod and grid, none of the signals being raised; Fig. 3, a rear elevation of the parts shown at the left in Fig. 2, showing one signal raised and the rear end of the corresponding key-lever raised to move the grid and thereby to operate the locking-rod; Fig. 4, a rear elevation of the signal and the upper part of its signal-rod and a part of the locking-rod, the latter being so broken as to show the projection on the front of said locking-rod, which, by moving under a corresponding projection on said signal-rod, supports said signal-rod; Fig. 5, a side elevation of the lever which raises the grid-locking hook to release said grid, its supporting-post, one of the fulerum-rod stands and a vertical section of the rocking plate and fulerum-rod through the slot of said plate (on line $x\ x$ in Fig. 8) at right angles to said fulerum-rod; Fig. 6, a side elevation of the alarm gong or bell, its supporting-post, the bell-hammer and its spring, the bell-

hammer-operating lever, its cam and supporting-post, the upper part of the bolt or till-holder, and a section of the rocking plate on the line $y\ y$ in Fig. 8, the dotted lines showing the position of said lever when said hammer is raised to strike the bell; Fig. 7, a side elevation of the mechanism shown in Fig. 1 and a vertical section of the rocking plate on the line $z\ z$ in Fig. 8; Fig. 8, a plan of the rocking plate and fulerum-rod; Fig. 9, a left-side elevation of the locking-rod, its downward projection, and the corresponding upward projection on the grid, these parts being in a position to unlock the locking-rod; Fig. 10, a like elevation of the same parts after the locking-rod has been released by the grid; Fig. 11, a plan of the registering-lever provided with a longitudinal rib, the registering-ratchet, the stop-wheel, and parts of the key-levers nearest the registering-lever with their hooks; Fig. 12, a right-side elevation of the key-levers provided with hooks, the registering-lever provided with a longitudinal rib, the rocking plate, the registering-ratchet, and stop-wheel and supporting-posts.

The case C, the key-levers K, turning on the fulerum-rod F, said rod being supported in brackets or stands $f\ f'$, secured to the table c of the case, the key-lever guides K', the signals S, supported upon vertical signal-rods S', each signal-rod resting upon one of said key-levers 80 and being guided in horizontal guides C' C'', supported upon vertical standards C' C'', said signals and levers being correspondingly numbered, are all substantially as shown and described in Letters Patent No. 377,342, dated January 31, 1888. As in the patent referred to, the grid D consists of vertical parallel rack-bars d, equal in number to the key-levers and connected to each other, said grid being pivoted at d' to the upper ends of parallel inclined links d'', which links are pivoted at their lower ends to brackets d'', fast on the table c, a spring, d'', pressing against one of the links d'' to hold the notched sides of the rack-bars against the key-levers to hold up the rear ends 90 of the key-levers when the key-levers are depressed, in the usual manner, the upper side, d'', of each of the upper notches, d'', being

longer than any of the notches below it and overhanging such lower notches, so that when the key-lever is engaged with the upper notch of its rack-bar, still further raising the rear 5 end of the key-lever moves the grid until none of the teeth of said rack-bar are immediately below said key-lever, as shown in Fig. 3, the grid being held in this position by a grid-locking hook, D', pivoted on a bracket, 10 c', on the guide C', catching over an upward projection, d', on the top of the grid to allow the key-lever to return to its position, substantially as shown and described in said patent. The links d' being inclined, as shown, 15 moving the grid to the right raises said grid. The vertical signal-rods are provided with horizontal projections s, as in said patent; but these projections extend to the rear of the signal-rods, instead of being forward projections, 20 and the locking-rod L is supported, substantially as described and shown in said patent, upon horizontal studs l', which enter the standards C' C', except that the locking-rod is in the rear of said standards and its locking 25 projections l' extend forward instead of backward.

In the accompanying drawings the locking-rod is represented as forced to the left, as one stands in front of the machine, by the spring l'. Instead of the means shown in said patent for moving the locking-rod against the pressure of the spring l', said rod is provided with a downward projection, l', the lower end, l', of which is bent horizontally backward, and the grid is provided with an upward 35 projection, d', the upper end, d', of which is bent horizontally forward and so arranged that when the grid is moved against the pressure of its spring d' the horizontal part of said last-named projection strikes against the horizontal part l' of the projection l' and moves the locking-rod L and its locking projections l' to the right of the machine—that is, to the left in Figs. 2, 3, and 4—to allow the projections s on the signal-rods to pass the projections l' as the signal-rods are raised. (See Figs. 40 2, 4, 9, and 10.)

When the locking-rod is moved sufficiently to the right and the signal is fully raised by the same key-lever which moves the grid, said 50 locking-rod is released by the rising of the grid and consequent lifting of the part d' above the part l', and the locking-rod is again forced to the left by its spring l', bringing the projections l' on the locking-rod under the corresponding 55 projections s of any signal-rods which may be raised at the time. The return motion of the locking-rod takes place before the return motion of the key-lever K, while the grid is still held by the hook D' and while the signal-rod 60 is held up by said key-lever.

The grid-unlocking lever M is a bent lever pivoted on a vertical post, P, at m, and having a rear arm, m', which extends nearly horizontally backward under the grid-retaining hook D', (see Figs. 1, 2, 5, and 7,) and having 65 also a downhanging front arm, m', slotted at its lower end at m', to receive and fit loosely the

horizontal cylindrical pin b, which closes the end of the slot b' in the rocking plate B. The rocking plate B is provided at its front edge 70 with ears b', which receive the fulcrum-rod F and allow said plate to rock on said rod. Said rocking plate B rests on all the key-levers K back of the fulcrum-rod, so that depressing any key-lever will raise the rear edge of said plate and carry the pin b upward in the slot m', and thereby (said slot being inclined upward and backward) will depress the rear end of the lever M and allow the free end of the hook D' to fall and engage the projection d' on the grid D, as above described, the grid being at the same time moved to the right by the depression of the key-lever, as above explained. When the key-lever is released, the plate B is restored to position by the contraction of a 85 spiral spring, m', attached to the lower end of the post P and to plate B, near its front edge, as shown in Fig. 5, thereby raising the rear end of said lever M and releasing the grid from the hook D by raising the latter. 90

The bolt F' is or may be precisely like the bolt shown in said patent, and its lower end is not therefore shown. It is sufficient to say that said bolt is long enough to reach down into the till in front of the back of the same, 95 or in front of a bracket secured to said back, to lock said till, and that the lower end of the bolt is beveled in such a manner as to be raised by said back or bracket when the till is pushed in, the dropping of the bolt by its own weight 100 locking the till, as shown in said patent.

The bolt F' is raised when any key-lever is depressed, and the plate B is rocked by an arm, b', on said plate, which arm extends laterally and backwardly under one of the ears f', with 105 which the bolt F' is provided.

The vertical hollow bracket f', secured to the table c, is used to guide the bolt F' vertically, and is provided (see Figs. 1 and 6) with a backwardly-extending slotted arm, f', which 110 receives and guides the T-shaped cam-piece H, said cam-piece having lateral ears h h', one, h', of which rests on the arm b' of the rocking plate, and is therefore raised by the depression of any key-lever K and the consequent 115 rocking of said plate. The other ear, h, of the cam-piece is inclined downward from back to front, both on the upper and under side. The post P' is supported on the table c, and has pivoted to it at p the bell-crank lever N, the lower end of which has a laterally-projecting cam, n, of the same shape as the ear h, and normally over but out of contact with said ear h, so that when the cam-piece H is raised the lower end of said lever N is thrown forward, and its rear end is depressed until the ear rises above the cam n, and the lever 120 N swings back to position by its own gravity, aided by the bell-hammer and hammer-actuating spring. When the rocking-plate B falls back to position, the cam-piece falls to position of its own weight, in so doing crowding back the cam n and the lower end of the lever N, which, immediately after the cam- 125

piece reaches its position, swings forward over said cam-piece.

On the post P' is secured the alarm-gong G, and above the gong on said post P' is pivoted 5 the bell-hammer g. One end of the spring-striking wire g' carries the hammer, and the other end thereof, after being wound, at g'', about the pivot g'', is secured to the post P' in front of a hammer-lever, g⁵, turning on said 10 pivot g⁵, the lower end of said lever resting against the under or left side of the striking-wire, all substantially as shown in said patent.

The upper end of the hammer-lever g⁵ extends under the rear end of the lever N, so 15 that when any key-lever K is depressed the hammer-lever is rocked by the rocking plate and lever N, and when the lever N returns to position the hammer-lever is turned back against the stop g' and the hammer strikes the 20 gong to call the attention of customers.

The registering devices shown in the drawings of the present application are substantially like those shown in Letters Patent No. 370,363, granted September 20, 1887, to said 25 Webster, and consist of a registering-lever, O, provided with a pawl, o, which engages a ratchet, O', turning on the same center with said lever O, and having secured to it a one-toothed pinion, (not shown,) which engages 30 with the teeth of a gear, O², and turns said gear one tooth at each complete revolution of said ratchet O', the teeth of said ratchet and gear being numbered and the lever turning said ratchet a number of teeth when any key-lever 35 is depressed equal to the number indicated by the figures borne by said key-lever, as fully described in said last-named patent.

With the registering devices above named 40 may be used the retaining and locking devices, index-fingers, and lever-guides shown in said last-named patent. The registering-lever is in the present invention prevented from being turned too far by its own momentum and registering on the ratchet O' an amount greater 45 than is marked on the depressed key-lever and indicated by the corresponding signal by hooks k², secured on the top of the key-levers K, respectively, back of the registering-lever, as shown in Figs. 1 and 7, so that when any key-lever 50 is depressed to its greatest extent the hook k² on said key-lever is raised and carried forward over the registering-lever, or over a longitudinal rib, o', cast or otherwise secured on the back of said registering-lever, the length 55 of the hooks k² so varying in length and distance from the fulcrum as to engage said registering-lever while the same rests upon their respective key-levers, and said key-levers are depressed to their greatest extent.

60 As an additional precaution, to prevent the ratchet O' and the registering-lever from moving too far, we secure to said ratchet O', concentrically therewith, a stop-wheel, O³, of larger diameter, and having its teeth either 65 straight or turned, as shown, in the other direction from the teeth of said ratchet O', and upon the vertical post P³, secured on the ta-

ble c by a horizontal stud, q, we pivot the bent lever Q in such a manner that the nearly-horizontal upper arm, q', of said last-named 70 lever extends backward over the stop-wheel O³, and will be forced into engagement with the teeth thereof when the lower arm, q², of said lever Q is thrown forward or raised by lifting the rear edge of the rocking plate B, (that is, 75 by the depression of any key-lever,) the end of the pin b above described entering a slot, q¹, in said lower arm, q², these parts being so arranged that when the ratchet O' has turned the angular distance measured by the number 80 of teeth corresponding with the number on the depressed key-lever the rear or pawl end of the lever engages the teeth of the stop-wheel O³ and prevents said stop-wheel, and therefore the ratchet O', from turning farther. 85 It will be seen that the lever Q is operated in substantially the same manner as the lever M. When the key-lever is let go and the rear edge of the plate B falls, the lever Q is thereby restored to position. The stop-lever Q and the 90 stop-wheel O³ absolutely prevent an excessive registration.

We claim as our invention—

1. The combination of the registering-ratchet, the registering-lever carrying a pawl 95 to engage said ratchet, key-levers arranged below said registering-lever, and each having a hook arranged farther from the fulcrum of said key-levers than said registering-lever, and each hook adapted to engage said registering-lever and prevent its further movement when the key-lever bearing said hook is depressed to its greatest extent, as and for the purpose specified.

2. The combination of a series of key-levers, 105 a grid connected to a suitable table or support by parallel inclined links, said grid consisting of parallel bars arranged in the spaces between said key-levers and having inclines at their upper ends, whereby the complete depression of any of said key-levers will move said grid laterally and upward, signals, vertically-guided signal-rods supporting said signals, arranged above said key-levers and adapted to be raised by the depression of the 110 same and having locking projections, a horizontal locking-rod having locking projections arranged above said first-named locking projections, said locking-rod having a downward projection bent backward at its lower end, and 115 said grid having an upward projection bent forward to engage the lower end of said downward projection on said locking-rod when said grid is moved laterally to move said locking-rod aside to allow said signal-rods to be raised, 120 and a spring to restore said locking-rod to position when said grid is raised to its full height to release said locking-rod and to hold up the signals raised by the depression of said key-levers, as and for the purpose specified.

3. The combination of a series of key-levers turning upon a fulcrum-rod, a rocking plate turning on said fulcrum-rod and arranged above all of said keys and having a laterally-

extending arm, a T-shaped cam provided with an ear resting upon said arm, and provided, also, with a cam or ear having a downward and forward incline on its upper and under 5 surface, a bent lever having a correspondingly-shaped cam at its lower end arranged above the incline of said T-shaped cam, a gong, a hammer, a hammer-lever, a spring to force said hammer toward said gong, said hammer 10 being supported upon said hammer-lever, and the end of said hammer-lever farthest from said hammer being arranged under the rear upper end of said bent lever, whereby the depression of any of said keys will rock said 15 plate and levers and sound said gong, as and for the purpose specified.

4. The combination of a series of keys mounted upon a common fulcrum-rod, the rocking plate mounted on said fulcrum-rod and extending over all of said keys and provided with a cylindrical pin, the grid consisting of a series of parallel vertical rack-bars and inclines at the top of said rack-bars overhanging the teeth of said rack-bars, respectively, said rack-bars being arranged in the spaces between the rear ends of said keys and having their toothed sides normally in contact with said keys, a hook pivoted and adapted to engage said grid and to prevent the same from returning to its 20 normal position when pushed aside by the rear ends of any of said key-levers acting upon said incline, a bent lever provided with a slot inclined upward and backward to receive the pin on said rocking plate and adapted to be 25 turned upon its fulcrum by the return motion of said rocking plate after said key-levers are restored to position, and to raise said pivoted hook out of engagement with said grid to allow said grid to return to its normal position, as 30 and for the purpose specified.

5. The combination of the registering-ratchet, the registering-lever carrying a pawl to engage said ratchet, numbered key-levers ar-

ranged below said registering-lever, each key-lever being adapted when depressed to move 45 said registering-lever and to rotate said registering-ratchet, a number of teeth corresponding to the number of said key-lever, a stop-ratchet secured to said registering-ratchet concentrically therewith, and a stop-lever adapted to be 50 operated by the depression of any of said key-levers to engage said stop-ratchet and to prevent the further rotation of said registering-ratchet when said key-lever is depressed to its greatest extent, as and for the purpose specified. 55

6. The combination of the registering-ratchet, the registering-lever carrying a pawl to engage said ratchet, numbered key-levers arranged below said registering-lever and having 60 a common fulcrum, each of said key-levers when depressed being adapted to move said registering-lever and to rotate said ratchet a number of teeth corresponding to the number of said key-lever, a toothed wheel secured to 65 said registering-ratchet concentrically therewith, a stop-lever provided with an arm extending over said toothed wheel and with another arm provided with a slot, a rocking plate provided with a pin or lateral projection 70 adapted to enter said slot, said rocking plate being adapted to be rocked by the depression of any of said key-levers and thereby to cause the first-named arm of said stop-lever to engage said toothed wheel and to prevent the 75 further rotation of said registering-ratchet when said key-lever is depressed to its fullest extent, as and for the purpose specified.

In witness whereof we have hereunto set our names, this 27th day of October, A. D. 1887, 80 before two attesting witnesses.
